His attorney.

UNITED STATES PATENT OFFICE.

JOHN D. HILLIARD, OF SCHENECTADY, NEW YORK, ASSIGNOR TO GENERAL ELECTRIC COMPANY, A CORPORATION OF NEW YORK.

OIL CIRCUIT BREAKER.

Application filed August 15, 1921. Serial No. 492,322.

This invention relates to electric switches of the high potential type and more particularly to those wherein the contacts are separated in oil or similar insulating liquid which is contained within a suitable vessel and wherein means is provided for the discharge from the vessel of material ejected by the arc which is formed when the contacts separate.

One object of the present invention is to provide a means to separate the ejected gas and oil and to permit the ready escape of the gaseous material so as to prevent an undue rise of pressure within the oil vessel. Means is further provided exterior to the vessel whereby the material may be cooled so that a portion of the same is condensed and returned to the main body of oil within the vessel and the remainder has its temperature so reduced that it may be safely allowed to escape into the atmosphere.

A further object is to provide means whereby the arc is extinguished by a separation of the electrodes in a large body of cool oil, provision being made whereby comparatively small quantity of oil will be ejected from the vessel. A further object of the invention is to provide means whereby the highly heated products of the arc are prevented from coming into contact with the oil vessel whereby the danger of a short circuit between the active electrodes and the metallic walls of the vessel is reduced to a minimum.

In the particular embodiment of my invention here illustrated the oil vessel is provided with stationary electrodes extending through the top thereof, which electrodes are formed with suitable vent passages which lead to the cooling and condensing chambers. The contacts are separated within these passages, the stationary electrodes thus serving as a shield to prevent the highly heated material from being blown against the sides of the oil vessel. The condensing chambers are supported above the oil vessel and are provided with baffles or similar means to assist in the cooling operation.

Other objects and advantages will appear from the following description taken in connection with the accompanying drawing wherein Fig. 1 is a sectional view, partly in elevation, of a switch embodying my invention; Fig. 2 is a sectional view on the line 2—2 of Fig. 1 showing one pair of stationary

and movable contacts, and Fig. 3 is a sectional view through one of the stationary electrodes taken on the line 3—3 of Fig. 1.

In Fig. 1 of the drawing, 10 represents a vessel adapted to contain oil or similar insulating liquid and provided with a cover 11. Arranged to move through an opening 12 formed in the cover 11 is an insulating rod 13 which carries a metallic bridging member 14 formed at its ends with contacts 15. These contacts are each formed of two spring members 17 adapted to embrace a stationary contact which is in the form of a bar 44 extending across the enlarged lower portion 28 of the hollow terminal stud 27. These studs are in the form of tubes and where they pass through the cover 11 are supported by the insulator bushings 29. The enlargements 28 are covered with insulating material 30 which extends into the enlargement and upwardly against its inner wall as far as the stationary contacts.

The tubes comprising the studs 27 extend some distance above the insulators and have secured within their upper portions plates 32 arranged at right angles to one another and joined together at their center. The plates 32 carry at their upper end a hemispherical baffle 33 and in addition carry conducting rods 34 which in turn carry a second baffle 35 of a form similar to baffle 33. Supported upon the insulators 29 and enclosing the baffles 33 and 35 are casings 37 which are adapted to form cooling chambers 38 for the material escaping from the vessel 10. A third baffle 40, which has an inverted frusto-conical surface, is secured to the casing 37 and lies intermediate the baffles 33 and 35. It will be seen that any oil which condenses on the surface of the baffles or walls of the condensing chambers will flow to the bottom of the chambers and be returned through openings 42 to the main body of oil within the tanks. Casings 37 are formed with over-hanging openings 42 for the discharge of the gases. These openings are formed at the sides most removed from the other casing so as to prevent the gases from bridging the space between the stationary electrodes. The conducting rods 34 extend upwardly through the top of the casing 37 and form terminals for the switch. Current contacts 43 are secured to the bridg-

ing member 14, while the cooperating contacts 44 are secured to the outer wall of the enlargement 28.

In practice the switch is opened by lowering 5 the operating rod 13 and the bridging member 14. The contacts 43 and 44 separate first, transferring the current to the arcing contacts 15 and 44. When these separate, the movable arcing contacts pass down 10 through a cool body of oil and the gases formed by the discharge are blown upwardly through the stud 27. Inasmuch as the contacts 15 and 44 are located near the surface of the oil but a small amount of oil is carried with the gases upward into the chamber 38 and as the opening in the tubular member is of large size this material passes 15 freely into the chamber 38 without causing any great rise of pressure within the vessel 20 sel 10.

As the gases ejected by the arc are confined within the studs 27 there is no opportunity for them to bridge the space between these electrodes and the vessel 10 and 25 there is, therefore, little danger of arcing over to the walls of the vessel.

If desired, quartz gravel may be placed in the casing 37 in the path of the material ejected by the arc for the purpose of cooling 30 the gases and separating the oil therefrom. A switch which employs gravel for this purpose is disclosed in my Patent Number 1,537,353, May 12, 1925, assigned to the same assignee as the present application.

35 In certain cases it may be advisable to provide cushioning means within the enlargement 28 to permit local expansion of gas generated therein. This may take the form of an inverted cup or trough arranged with- 40 in the enlargement 28 near the sides thereof, which cup or trough is open at its bottom and is adapted to contain gas. The gas is compressible and thus furnishes a cushion for the expansion of the arc gases.

45 What I claim as new and desire to secure by Letters Patent of the United States, is:—

1. An electric switch comprising a closed vessel containing insulating liquid, relatively movable contacts separable in the liquid, and 50 means comprising a tubular member open at both ends for forming a circuit connection between one of said contacts and the exterior of the vessel and for forming a path for the quick discharge of gas from the vessel.

55 2. An electric switch comprising a closed vessel containing insulating liquid, stationary and movable contacts separable in the liquid, and a hollow terminal stud for the

stationary contact passing through the top of the vessel and open at both ends, said 60 stud providing a free path therethrough for the quick discharge from the vessel of gas formed therein.

3. An electric switch comprising a vessel containing insulating liquid, a stationary 65 contact and a movable contact separable in said liquid, an insulator bushing secured in the top of said vessel, a hollow terminal stud passing through said bushing and connected at one end with said stationary contact, and 70 cooling and separating means at the other end of said stud, said stud providing a path for the quick discharge of gas and liquid ejected from the vicinity of said contacts and forming a protection for the bushing 75 against the pressure of the material being ejected.

4. An electric switch comprising a vessel having a cover thereon and containing insulating liquid, the level of which is spaced below the cover, a stationary contact and a movable contact separable in the insulating liquid, an insulator bushing mounted in said cover, a terminal stud comprising a metal tube fitting in the insulator bushing and 80 having an enlargement at its inner end enclosing and connected with stationary contact, a cooling and separating chamber connected with the outer end of said stud, the material ejected by an arc between said contacts being collected and quickly discharged through the tube comprising said stud and the insulator bushing being protected from the pressure of said material by said tube.

5. An electric switch comprising a vessel having a cover thereon and containing insulating liquid, the level of which is spaced below the cover, a pair of insulator bushings mounted in the cover, a tubular terminal stud supported in each insulator bushing and 100 having an enlarged portion at its inner end, a stationary contact carried by said stud in the enlarged portion thereof, a movable bridging member having contacts at its ends for engaging the stationary contacts, an operating rod therefor, a metallic casing having cooling and separating means therein for gas and liquid ejected from an arc formed between the contacts, said studs being constructed to quickly discharge the ejected material from said vessel and relieve the insulator bushings of the pressure thereof.

In witness whereof, I have hereunto set my hand this 12th day of August, 1921.

JOHN D. HILLIARD.
